SLATTED AWNING

Carroll B. Grant, Dallas, Tex.

Application September 23, 1939, Serial No. 296,310

16 Claims. (Cl. 156—15)

This invention relates to awnings and is concerned principally with rigid awnings of the slatted type.

An object of the invention is to provide a rigid awning capable of installation as a more or less permanent building fixture, and one which is comprised of slats arranged to provide for free passage of air therebetween while excluding the passage of rain.

Another object is to provide an awning that is self-ventilating over its entire area and which is of rigid, durable, and economical construction.

Other objects will be apparent from the description.

15 In the accompanying drawings:

Figure 1 is a front elevation of an awning constructed in accordance with the invention.

Figure 2 is a side elevation thereof.

Figure 3 is a rear elevation of the awning.

20 Figure 4 is a vertical section taken on the line 4—4 of Figure 3.

Figure 5 is a fragmentary section taken on the line 5—5 of Figure 1.

Figure 6 is a fragmentary transverse section through a portion of the structure.

25 Figure 7 is a section taken on the line 7—7 of Figure 6.

Figure 8 is a section similar to Figure 6 but illustrating an alternative structural embodiment.

30 Figure 9 is a section taken on the line 9—9 of Figure 8.

Figure 10 is a section, also similar to Figure 6, illustrating another alternative structural form.

Figure 11 is a section, like Figure 6, illustrating 35 a still further alternative structure.

In all embodiments, the awning comprises a plurality of somewhat closely spaced parallel slats disposed on the same side of transversely extending cleats to which they are rigidly secured.

40 The spaces between the slats are occupied by drainage gutters, side edge portions of which are disposed beneath overlying adjacent side edges of the slats and in spaced relation thereto to provide air passages through which air may pass freely.

45 The awning may have end sections of substantially similar construction. The disposition of the gutters with respect to the slats is such that direct rays of sunlight are prevented from passing through the awning as well as rain and sleet.

50 The embodiment illustrated in Figures 1 to 7, inclusive, is constructed with an appropriately inclined face portion composed of a plurality of slats 12 alternated with slats 13, all slats being identical, and all being disposed in parallel spaced

relation with no overlapping thereof. The series of slats 12 occupy a common plane and are directly attached by appropriate securing elements 14 to subjacent transverse cleats 15 arranged in parallel spaced relation across the inner face of the awning from one end to the other. The alternate series of slats 13 likewise occupy a common plane, but they are elevated with respect to the slats 12 by means of spacer blocks 15 seated on the outer faces of the cleats 15 and attached thereto by means of others of the securing elements 14 which are employed to secure the slats to the filler blocks and cleats. As will be apparent from Figures 5 and 6, the plane of the slats 13 parallels that of the slats 12 and is appreciably elevated with respect thereto, and the opposed side edges of adjacent slats occupy spaced parallel planes that are perpendicular to the cleats.

Along the top edge of the awning one of the 20 cleats 15 is in flush relationship with the squared ends of the slats, and carries appropriate attaching fixture means 16 by which the awning may be mounted in service position. The bottom ends of the slats extend beyond the lowermost cleat 25 and are dressed with substantially tapered terminal portions or tips to provide a decorative effect.

Where desired, the awning is further provided with end sections, here shown as comprised of 30 parallel, spaced, vertical slats 17 having inclined upper ends conforming to the pitch of the face portion and secured to a similarly inclined cleat 18 which is appropriately secured to the cleats 15. The lower end portions of the slats 35 are connected by attachment to a horizontal cleat 19 which carries at its inner end an attachment fixture 20.

The face portion of the awning is further provided with drainage gutters 21 occupying the 40 spaces between the slats 12 and 13 and extending longitudinally of the slats over all of the underlying transverse cleats 15, to which they are attached by means of others of the securing elements 14. These gutters comprise angle strips of metal preferably possessing some degree of inherent resiliency, and are disposed with their apices seating on the cleats and with their flange portions bearing tightly at one side against the adjacent side edges of the slats 12 and at the other side against the adjacent ends of the 45 filler blocks 15.

An important structural feature of the invention resides in the fact that, as shown best in Figure 6, the side edges of the elevated slats 13 50

slightly overhang the ends of the filler blocks 15'. The divergent flanges of the gutters are proportioned to the discrepancy in adjacent slat elevation, one being short on that side which abuts the edge of one of the lower slats 12 and the other being long on that side which abuts the ends of the filler blocks. The edge of the short flange 22 is substantially flush with the top face of its abutting slat 12, and the edge of the long flange 23 10 is disposed beneath the overhang of the adjacent elevated slat 13 and is spaced from and below the under face of the slat, leaving an air passage 24 that is protected by the covering overhang of the slat edge and through which air may pass freely. 15 In placing the gutters 21 their flanges are somewhat compressed toward each other and are thus placed under tension which insures their firm frictional binding engagement against their respective abutments. Figure 5 indicates that, by 20 virtue of this engagement, the use of the securing elements 14 shown in Figure 6 may be dispensed with if desired.

In the embodiment illustrated in Figures 8 and 9, the slats 12a and 13a occupy a common 25 plane and are directly connected to the cleats 15a. The slats are in parallel spaced relation with their opposed side edges slightly overhanging the straight side walls of squared recesses 25 provided in the cleats and opening to their upper 30 faces. Channel shaped gutters 21a are seated in the cleat recesses, extending longitudinally between the slats, with their side flanges 22a and 23a flatly abutting the side walls of the recesses and terminating in spaced relation beneath the 35 overhanging under faces of the slats; providing protected air passages 24a.

The embodiment disclosed in Figure 10 combines the principle of staggered slat elevation with that of the squared cleat recess and channelled 40 gutter. In this form, the slats 12b and 13b occupy different planes, with the slats 13b elevated above the slats 12b and being supported on filler blocks 15b on the cleats 15b. The cleats are provided with the squared recesses 25b seating channelled 45 gutters 21b whose parallel side flanges 22b and 23b terminate in spaced relation beneath the overhanging side edge portions of the adjacent slats and leave air passages 24b.

The structural arrangement shown in Figure 11 50 is similar to that of Figure 5 except that the slats 13c are depressed with respect to the slats 12c, being seated directly on the flat bottoms of wide seating recesses 25c provided in the cleats 15c. In this embodiment the slats 12c are secured 55 directly to the top faces of the cleats without the interposition of spacer means, their elevation being obtained by the depressed relationship of the slats 13c, and angle gutters 21c, identical to the gutters 21 previously described, are secured in the cleat recesses 25c along each side edge of the slats 13c, against which the short flanges 22c of the gutters abut. The long flanges 23c of the gutters abut the adjacent side walls of the cleat recesses and terminate in spaced relation beneath the 60 overhanging side edges of the adjacent slats 12c to leave air passages 24c.

It is preferred that the awning, with exception 65 of the drainage gutters, be constructed of wood, although it may equally as well be made of metal or composition slat construction. The spacer means for elevating certain of the slats may be integral with the cleats, and any desired variations in the details of structure and arrangement of the various parts may be made that fall within 70 the scope of the invention as claimed.

I claim:

1. An awning comprising a plurality of parallel slats disposed in spaced relation, cleat means extending transversely across said slats and supporting the slats, all of said slats being disposed 5 on the same side of said cleat means, and drainage gutters carried by said cleat means on the same side as the slats and extending longitudinally of the slats in the spaces therebetween.

2. An awning comprising a plurality of slats 10 arranged in spaced relation and having parallel side edges, the opposed side edges of adjacent slats being spaced apart, cleat means extending transversely across said slats and supporting the slats, all of said slats being disposed on the same side 15 of said cleat means, certain of said slats being elevated with respect to the others, and drainage gutters occupying the spaces between the opposed side edges of adjacent slats and on the same side of the cleat means.

3. An awning comprising a plurality of slats disposed in parallel spaced relation, cleat means supporting said slats and extending transversely across the slats, all of said slats being disposed on the same side of the cleat means and alternate 25 slats being in different planes, and drainage gutters carried by said cleat means in the spaces between the opposed side edges of adjacent slats and on the same side therewith.

4. An awning comprising a plurality of slats 30 disposed in parallel spaced relation, cleat means supporting said slats and extending transversely across the slats, all of said slats being at the same side of the cleat means, alternate slats being disposed in different planes, drainage gutters carried 35 by said cleat means in the spaces between said slats and on the same side therewith, and said gutters having side walls spaced with respect to certain of said slats to provide air passages therebetween.

5. An awning comprising a plurality of slats arranged side by side with their side edges in parallel spaced relation, cleats supporting said slats and extending transversely across all of the slats on the same side thereof, drainage gutters seated on said cleats in the spaces between the opposed edges of the slats and on the same side therewith, and the side edges of certain slats overhanging the adjacent side walls of the gutters and in spaced relation thereabove to provide air 50 passages.

6. An awning comprising a plurality of slats arranged side by side with their side edges in parallel spaced relation, alternate slats being disposed in different planes and out of overlapping 55 relation, cleats supporting the slats and extending transversely thereof, and drainage gutters carried by the cleats in the spaces between the slats.

7. An awning comprising a plurality of slats 60 arranged side by side with their opposed side edges spaced apart, cleats supporting the slats and extending transversely thereof, the spacing of said opposed side edges of the slats being in the direction in which the cleats extend, and drainage gutters seated on said cleats between the opposed side edges of the slats and on the same side therewith.

8. An awning comprising a plurality of slats arranged side by side with their opposed side 70 edges spaced apart, cleats supporting the slats and extending transversely entirely thereacross, the spacing of said opposed side edges of the slats being in the direction in which said cleats extend, drainage gutters on the cleats in the 75

spaces between the slats and on the same side therewith, and each gutter being spaced from an adjacent slat to provide an air passage therebetween.

5 9. An awning comprising a series of slats disposed in parallel spaced relation in a common plane, a second series of slats disposed in parallel spaced relation in a common plane and elevated with respect to the first plane, said slats 10 being staggered without overlapping, cleat means supporting all said slats and at the same side thereof, and drainage gutters on the cleat means between the opposed edges of adjacent slats and on the same side therewith.

15 10. An awning comprising a series of slats disposed in parallel spaced relation in a common plane, a second series of slats disposed in parallel spaced relation in a common plane and elevated with respect to the first plane, said slats being 20 staggered without overlapping, cleat means supporting all said slats and at the same side thereof, drainage gutters on the cleat means and extending longitudinally between adjacent slats and on the same side therewith, said elevated slats at their side edges overhanging a wall portion of an adjacent gutter.

25 11. An awning comprising a series of slats disposed in parallel spaced relation in a common plane, a second series of slats disposed in a common and different plane and staggered with respect to the first series without overlapping, cleat means supporting all said slats and at the same side thereof, drainage gutters on the cleat means and extending longitudinally between adjacent slats on the same side therewith, the side edges of the second series of slats overhanging a wall portion of an adjacent gutter, and said wall portion being spaced from and beneath the adjacent overhanging slat edge to provide an air passage.

30 12. An awning comprising a series of slats disposed in parallel spaced relation in a common plane, a plurality of slats staggered with respect to said series and each in a plane different from that of the series, cleat means common to all of said slats and on the same side thereof, and

drainage gutters on said cleat means extending longitudinally of the slats and occupying the spaces between their side edges on the same side therewith.

35 13. In an awning, a plurality of cleats, a series of slats secured thereto in parallel spaced relation, a second series of slats secured to the cleats on the same side as the first series and staggered with respect to said first series without overlapping, the side edges of the slats of said first series being transversely spaced from the opposed side edges of adjacent slats of said second series, and drainage gutters on said cleats on the same side as the slats extending longitudinally between the slats and substantially filling the spaces between the opposed side edges thereof.

40 14. In an awning, a plurality of cleats, a series of slats secured thereto in parallel spaced relation, a second series of slats staggered with respect to said first series in parallel spaced relation thereto and without overlapping, means on said cleats supporting said second series on the same side of the cleats as the first series, drainage gutters on said cleats between the slats, and said gutters having side walls abutting the side edges of one series of slats on one side and spaced from and beneath the side edges of the second series of slats on the other side.

45 15. In an awning, a plurality of slats disposed in parallel spaced relation substantially in a common plane, spaced cleats supporting said slats from one side thereof, said cleats being recessed between the slats and beneath the side edges thereof, and drainage gutters seated in said recesses.

50 16. In an awning, spaced cleats, a plurality of slats disposed in parallel spaced relation and differently elevated with respect to the cleats, all of said slats being secured to the cleats at the same side thereof, and substantially V-shaped drainage gutters seated at their apices on said cleats and extending longitudinally in the spaces between the opposed side edges of adjacent slats and on the same side therewith.

CARROLL B. GRANT.
